(57) **CLAIM**

The ornamental design for a package for consumable products, as shown and described.

DESCRIPTION

FIG. 1 is a front elevation view of a package for consumable products, showing our new design;

FIG. 2 is a rear elevation view thereof;

FIG. 3 is a front, right side perspective view thereof;

FIG. 4 is a front, left side perspective view thereof;

FIG. 5 is a right side elevation view thereof;

FIG. 6 is a top plan view thereof;

FIG. 7 is a bottom plan view thereof; and,

FIG. 8 is a front elevation view thereof, wherein the cover is in an open position.

In the drawings, the broken lines depict environmental structure that form no part of the claimed design.
